UNITED STATES PATENT OFFICE

ALFRED E. ISCHINGER, OF READING, PENNSYLVANIA, ASSIGNOR TO BERKSHIRE KNITTING MILLS, OF WYOMISSING, PENNSYLVANIA, A CORPORATION OF PENNSYLVANIA

DESIGN FOR A STOCKING

Application filed June 26, 1931. Serial No. 40,328. Term of patent 14 years.

To all whom it may concern:

Be it known that I, ALFRED E. ISCHINGER, a citizen of the United States of America, residing at Reading, in the county of Berks and State of Pennsylvania, have invented a new, original, and ornamental Design for a Stocking, reference being had to the accompanying drawing forming part thereof.

The drawing is a side view of a stocking embodying my ornamental design, the opposite side thereof being the same.

I claim:

The ornamental design for a stocking, as shown and described.

In testimony whereof I affix my signature.

ALFRED E. ISCHINGER.
